[57] **CLAIM**

The ornamental design for a combined bulb-and-shield for a high voltage detector, as shown and described.

DESCRIPTION

FIG. 1 is a side elevational view of a combined bulb-and-shield for a high voltage detector showing my new design, the opposite side being a mirror image but for two small rectangles which appear opposite and in place of the single elongated rectangle on the shield; FIG. 2 is a top plan view of the combined bulb-and-shield;

FIG. 3 is a bottom plan view of the combined bulb-and-shield; and

FIG. 4 is a right end elevational view of the combined bulb-and-shield, the left end elevational view being a mirror image thereof.
